(57) **CLAIM**

The ornamental design for a storage cabinet, as shown and described.

DESCRIPTION

FIG. 1 is a front, top, and right perspective view for a storage cabinet showing my new design;

FIG. 2 is a front, bottom, and left perspective view thereof;

FIG. 3 is a rear, top, and right perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a front, top, and right perspective view thereof, when the door of the storage cabinet is closed; and,
FIG. 11 is an enlarged detail view taken from the encircled area in FIG. 2.

The dash dot broken lines shown in the figures are included to identify areas of enlargement and form no part of the claimed design. The evenly spaced broken lines depict portions of the article that form no part of the claimed design.

1 Claim, 11 Drawing Sheets
